UNITED STATES PATENT OFFICE.

JAMES I. GEMMILL, OF PONTIAC, MICHIGAN, ASSIGNOR OF ONE-HALF TO WM. A. LUDLOW, OF PONTIAC, MICHIGAN.

EXPLOSIVE-MIXTURE COMPRESSOR.

Application filed January 23, 1924. Serial No. 683,114.

To all whom it may concern:

Be it known that I, JAMES I. GEMMILL, a citizen of the United States of America, residing at Pontiac, in the county of Oakland and State of Michigan, have invented 5 certain new and useful Improvements in Explosive-Mixture Compressors, of which the following is a specification.

This invention relates to new and useful 10 improvements in explosive mixture compressors for internal combustion engines.

An important object of the invention is to provide a compressor adapted to be interposed between a combustion engine and 15 carbureter for delivering fuel to the intake valves under a greater pressure than the atmospheric pressure produced by the suction of the piston within the engine.

A further object of the invention is to 20 provide a device of the above mentioned type which is of simple construction, efficient in operation, cheaply manufactured, and one that may be quickly and easily applied to the present, standard makes of internal combustion engines.

Other objects and advantages of the invention will be apparent during the course 25 of the following description.

In the accompanying drawing forming a 30 part of this specification and in which like numerals are employed to designate like parts throughout the same.

Figure 1 is a side elevational view, partly 35 in section, of the explosive mixture compressor embodying this invention, and

Figure 2 is an end elevational view of a compressor fan employed in connection with this invention.

In the drawing, wherein for the purpose 40 of illustration is shown a preferred embodiment of this invention, the numeral 5 designates a single intake and double discharge manifold pipe having a flanged intake 6 and a pair of spaced, flanged discharge ends 7 and 8, as illustrated. The flange 6^a, forming part of the intake 6, is to be suitably connected to the carbureter associated with an internal combustion engine. The flanges 7^a and 8^a of the discharge ends 7 and 8 of the 45 manifold pipe 5 are intended to be suitably connected to the elbows 9 and 10 by means of the flanges 9^a and 10^a carried by the intake ends 11 and 12 of the said elbows 9 and 10. The discharge ends 13 and 14 of the 50 elbows 9 and 10 are provided with flanges

13^a and 14^a to which are secured the flanges 15^a and 16^a of the nipples 15 and 16. These nipples 15 and 16 are further provided with flanges 15^b and 16^b at their adjacent ends to which are secured the flanges 17^a of the 60 coupler 17. It will be seen that this coupler 17 is provided with a flanged discharge opening 18 to which the intake manifold, leading to the combustion chambers of the engine, is to be attached. It will be seen, by inspecting Fig. 1, that this coupler 17 is provided with an integral, inwardly projecting fin 19 which is in axial alinement with the discharge opening 18 of the said coupler.

The elbows 9 and 10 are provided with inwardly directed, axially alined annular bosses 20 and 21 which are adapted for receiving the roller bearings 22 which are provided for anti-frictionally supporting the shaft 23, as illustrated. Secured to the shaft 75 23, in juxtaposition to the roller bearings 22, are the movement limiting collars 24 which are suitably secured to the shaft 23 and are employed for preventing longitudinal shifting of the said shaft. The elbow 9 is further provided with an integral nipple 25 which is provided for carrying the stuffing box 26 which is employed for preventing the escape of fuel around the projecting end 23^a of the shaft 23.

Mounted upon the shaft 23 and positioned within the nipples 15 and 16 are oppositely inclined fans 27 which each consist of a hub portion 28, suitably keyed to the shaft 23, and having an integral, annular flange 90 or disk 29, as illustrated. Suitably secured to or formed integrally with the hub and annular flange 28 and 29 of each fan 27 are the fan blades 30 which, as illustrated in Fig. 2, are of curved profile. It will be seen 95 that these fan blades are beveled, as at 31, at their outer edges.

Suitably clamped between the flanges 14^a and 16^a of the elbow 10 and nipple 16 and between the flanges 13^a and 15^a of the elbow 9 and nipple 15 are the apertured disks 32 which are formed for permitting the passage of fuel into the pockets formed by the fan blades 30 at the reduced ends of said fans 27. Suitably secured to or formed integrally with the apertured disks 32 are the thimbles 33 which surround the beveled edges 31 of the fan blades 30 and are positioned in proximity to said edges.

It will readily be understood that if the 110

flange 6^a of the intake 6 of the manifold pipe 5 is connected to a carbureter and power applied to the projecting end 23^a of the shaft 23 for rotating the said shaft in the proper direction, fuel will be sucked from the carbureter and drawn through the elbows 9 and 10, from the discharge ends 7 and 8 of the manifold pipe 5 by the fans 27. The fuel will be admitted to the fans through the apertures 32^a of the disks 32 and will be discharged by the fans through the annular openings 29^a surrounding the annular flanges 29 carried by the fan hubs 28. It will be seen that the fuel discharged by the fans 27 will enter the interior of the coupler 17 and that the inwardly projecting fin 19 will have a tendency to direct or steer the fuel toward the discharge opening 18 of the coupler.

20 It is now believed that the construction and operation of this device will be understood, by those skilled in the art, without any further description of the same.

It is to be understood that the form of this invention herewith shown and described is to be taken as the preferred example of the same, and that various changes in the shape, size, and arrangement of parts may be resorted to without departing from the spirit of the invention or the scope of the subjoined claims.

Having thus described the invention, I claim:—

1. In a device of the class described, a single intake and double discharge manifold pipe, an elbow connected to each discharge of said pipe, a nipple connected to each of said elbows, a three-way coupler connecting said nipples, a shaft extending axially through said nipples, a fan in each of said nipples keyed to said shaft and having fan blades provided with beveled outer edges, said fans each having a central annular inlet and a peripheral annular outlet, and a thimble positioned within each of said nip-

ples surrounding said fan and formed to correspond with the beveled edges of said blades.

2. In a device of the class described, a cylindrical fuel passageway, a shaft extending axially through said passageway, a hub keyed to said shaft, an annular flange carried by one end of said hub, a plurality of radially curved fan blades carried by said hub and flange and having beveled outer edges, and a cone-like thimble non-rotatable carried by said annular passageway surrounding said fan blades and conforming with the beveled edges thereof.

3. In a device of the class described, a fan comprising a hub, an annular outwardly directed flange carried by one end of said hub, a series of tangential fan blades carried by said hub and flange, said fan blades having their outer edges beveled longitudinally.

4. In a device of the type described, a fuel conduit having a lateral inlet at each end and an oppositely extending lateral outlet intermediate said ends, a fin projecting into the bore of the conduit in axial alignment with said lateral outlet, a shaft journaled axially in said conduit, a pair of hubs each of which has a concentric annular flange formed on the inner end thereof which is of less diameter than the diameter of the bore of the conduit, said hubs and their flanges being keyed to said shaft intermediate the inlets and the outlet, a series of tangentially extending blades carried by each of said hubs and flange structures, the outer edges of said blades being beveled, and immovable cone-like thimbles surrounding the blades carried by each hub and conforming with their beveled edges, and annular disks connecting the smaller ends of said thimbles to said conduit.

In testimony whereof I affix my signature.

JAMES I. GEMMILL.
